(57) **CLAIM**

The ornamental design for a light, as shown and described.

DESCRIPTION

FIG. 1 is a perspective view of the light with the bezel fully extended.

FIG. 2 is a bottom view of the light with the bezel fully extended as illustrated in FIG. 1;

FIG. 3 is a top view of the light with the bezel fully extended as illustrated in FIG. 1;

FIG. 4 is a right side view of the light with the bezel fully extended as illustrated in FIG. 1;

FIG. 5 is a left side view of the light with the bezel fully extended as illustrated in FIG. 1;

FIG. 6 is an end view of the light illustrated in FIG. 1, taken from the light end;

FIG. 7 is an end view of the light illustrated in FIG. 1, taken from the switch end; and,

FIG. 8 is a perspective of the light illustrated in FIG. 1 with the bezel retracted.

The broken line showing represents portions of the article not claimed and forms no part of the claimed design.
